UNITED STATES PATENT OFFICE.

JOHN WILSON BROWN, JR., OF PHILADELPHIA, PENNSYLVANIA.

AUTOMATIC MOLDING-MACHINE.

SPECIFICATION forming part of Letters Patent No. 567,884, dated September 15, 1896.

Application filed December 22, 1893. Serial No. 494,496. (No model.)

To all whom it may concern:

Be it known that I, JOHN WILSON BROWN, Jr., a citizen of the United States, residing in Philadelphia, Pennsylvania, have invented 5 certain Improvements in Automatic Molding-Machines, of which the following is a specification.

The object of my invention is to so construct an automatic molding-machine, that is, a machine for preparing the mold for casting, in such a manner that the flasks will be filled, packed, and cleaned off ready for removal by the machine itself, my invention relating to the special construction of the machine by 15 which this object is attained.

In the accompanying drawings, Figure 1 is a plan view of my improved molding-machine. Fig. 2 is a sectional elevation on the line 2 2, Fig. 1. Fig. 3 is a sectional elevation on the 20 line 3 3, Fig. 1. Fig. 4 is a sectional view of the base portion on the line 4 4, Fig. 1; and Fig. 5 is a sectional view on the line 5 5, Fig. 3.

A is the base of the machine, upon which is mounted the standard B. This standard extends through the center of the machine and 25 around it the several parts revolve.

B' is a post, and connecting this post with the standard B is a cross-frame B², in which is formed the hydraulic cylinder B³ of the 30 press for compressing the sand in the mold.

C is the driving-shaft, having fast and loose pulleys c c', as clearly shown in Fig. 4. This shaft is adapted to suitable bearings in the base of the machine and is provided with a 35 worm C', meshing with a worm-wheel C² on the hub of the pawl-arm C³, carrying a pawl c², engaging with internal teeth c³ on the worm-wheel. The object of this construction is to automatically stop the machine at every quar- 40 ter-turn. A slide-rod d, adapted to slide in suitable bearings, normally rests in the path of the pawl c², as clearly shown in Fig. 3, thus throwing the pawl out of engagement with the worm-wheel and preventing the arm 45 moving with said worm-wheel, and as this arm is secured to the shaft C', through which motion is imparted to the machine, it will be seen that the mechanism will be stopped until the pawl is released by the withdrawal of 50 the rod d. This rod, as clearly shown in Fig. 4, is connected to an arm d' of a shaft D, mounted in suitable bearings, and on this

shaft is a platform-lever D', having on one arm a platform D², and a counterbalance-weight D³ hung to the other arm, so that 55 when the operator steps on the platform to remove the finished mold the lever is depressed sufficiently to throw the rod d out of contact with the pawl c², allowing it to engage the teeth of the worm-wheel C², and 60 consequently setting the machine in motion; but when the operator steps from the platform to carry the mold away from the machine the weight D³ moves the pin into the path of the pawl, so that when the parts have 65 turned one-quarter of a revolution they will be automatically stopped until the operator again steps upon the platform.

On the shaft C⁴ is a miter-wheel c⁴, which meshes with a miter-wheel c⁵ on a vertical 70 shaft C⁵, which extends through the standard B. This shaft is mounted in a bearing b at the base and a bearing in the cap b', secured to the upper end of the standard B.

On the upper end of the shaft is a miter-wheel c⁶, meshing with a miter-wheel c⁷ on a horizontal shaft C⁶. This shaft operates the sand-valve and the releasing-valve, so that the compression-plunger may be elevated 75 clear of the flask. 80

On the shaft C⁴ is a wiper e, which engages with the star-wheel e' on a shaft E. The construction of the parts e e' is such that when the wiper-arm e² is not operating to move the wheel e' the wheel is locked, as clearly shown 85 in Fig. 3.

On the hub of the star-wheel e' is a miter-wheel e³, meshing with a miter-wheel e⁴, secured to the hub E' of the carrying-frame E². This hub finds its bearing upon the standard 90 B, and between the hub and the base of the standard are antifriction-rolls b².

On the carrying-frame are mounted the several platforms, four in the present instance, which support the flasks, so that the frame 95 will be moved through the medium of the star-wheel one-fourth of a revolution, then locked in position, and then moved again one-fourth of a revolution, and so on, allowing sufficient time for filling the flask with sand, ramming of the flask, and the removal of the flask from the machine. On each arm of the carrying-frame E² is mounted a vertically-movable plunger F, carrying at its upper end 100

the pattern-support f and at its lower end the traction-wheel f' , adapted to travel upon the cam-rail A' , secured to the base of the machine. This rail is of an even height except at one point, which is depressed sufficiently to allow the pattern to clear the mold before the operator removes the mold from the machine, as clearly shown in Fig. 2. Secured to each plunger and to the frame are flexible covers f^2 , which prevent the sand gaining access to the bearings of the plungers.

Mounted upon each arm of the carrying-frame E^2 are supports E^3 for the stripping-plates E^4 , supporting the flasks, and into each plate passes a pattern-support f , as clearly shown in Fig. 2, closing the bottom of the flask allowing it to be filled with sand. Pins on the stripping-plate E^4 enter openings in the supports E^3 , preventing the plate from turning. On each pattern-support are lugs f^3 , which project under the plate E^4 and have set-screws by which the plate and head may be aligned so that the plate is supported by the head.

25 Mounted in extensions at the rear of each support is a shaft g , on which is mounted a lever G , carrying the forked arm G' , to which is pivoted at g' the false flask G^2 , which rests upon the flask X , so as to allow sufficient sand 30 to be placed in the flask so that when the flask travels under the compressor and the sand is compressed by the plunger so much of the sand in the false flask will be pressed into the mold as may be necessary to give the density required, the sand remaining above the flask 35 being removed by the strike-off N .

The lever G is connected to a lever G^3 , pivoted at g^2 to lugs on the under side of the carrying-frame, and on this lever G^3 is a traction-wheel g^3 , bearing against the inner surface of a rail A^2 , secured to the base of the machine. The lever G is connected to the lever G^3 by a connecting-rod g^4 , having a take-up nut g^5 .

45 The rail A^2 is a cam-rail and so formed that it will force the false flask G^2 down upon the flask X and hold it there until the flask is filled with sand and the sand compressed, after which it will allow the false flask to be 50 elevated clear of the flask, so that it can be withdrawn and another flask placed in its stead.

Depending from the under side of the carrying-frame E^2 are arms H , on which are mounted scrapers h , connected together by a ring h' . These scrapers travel in a trough A^3 , formed by the base of the machine and the rails $A' A^2$. Into this trough falls the waste sand that escapes from the mold, and the 60 scrapers carry the sand to a discharge-opening a , Fig. 2, under which is a receptacle a' for receiving the collected sand.

On the hub E' is an inclined hood E^5 , which overlaps an inclined hood A^4 , in the present 65 instance forming a part of the casting of the rail A^2 . A tongue e^5 enters a groove e^6 in the hood A^4 , and in this groove is poured

sufficient mercury to make a mercury seal, so that the parts under the hood will be completely protected from the sand.

Secured under the base A of the machine is a sheet-iron tank A^5 , surrounding the gearing on the shaft C^4 . This tank is secured to the base in the present instance by a clamp-plate a^3 , and the joint is oil-tight. The joint 75 between the rail A^2 and the base is also oil-tight.

The driving-shaft C and the rod d pass through packing-boxes in the frame A , so that the bottom of the machine can be filled 80 with oil, forming an oil-tank. The oil is not only utilized to lubricate the parts of the machine, but is used as the motive fluid for the compression-plunger. The oil is drawn from the base by a pump J and forced through the 85 pipe J' into the cylinder B^3 . The oil is discharged through the pipe J^2 into the standard B . In the upper portion of the hub E' is an annular groove e^6 . Extending into this groove 90 is a tongue depending from the cap J^3 , and in the groove is sufficient mercury to form a 95 mercury seal. I also form a mercury seal b^4 between the cap b' and the miter-wheel c^6 , as clearly shown in Fig. 3.

J^5 is an automatic valve by which the oil 95 under pressure is released when a certain pressure is reached, but the valve is also positively operated by a cam j on the shaft C^6 , acting upon a lever j^3 , pivoted at j^2 and connected to the plunger j^4 . On this lever is an adjustable 100 weight j^5 , which returns the lever after being raised by the cam. By adjusting the weight the pressure can be regulated.

Referring now to Fig. 3, K is the plunger for forcing the sand into the mold. This plunger is adapted to the cylinder B^3 , and is provided at its lower end with a fluid cushion K' , so that the bottom of the plunger will conform, to a certain degree, to the irregularities of the pattern and to the irregularities 110 of the sand, thus ramming the mold more evenly than if a rigid plunger was used. An extension K^2 of the plunger has a recessed portion k , in which rests the pin of a crank k' , mounted on the shaft C^6 , so that after the 115 plunger is depressed the crank elevates it clear of the mold. Secured to the lower portion of the cylinder B^3 and to the plunger is a flexible cover k^2 , which prevents the sand gaining access to the space between the 120 plunger and the cylinder.

L is the sand-hopper, and in the bottom of this hopper is a sliding valve L' , operated by a crank L^2 on the shaft C^6 , through the rod l , arms l' , shaft L^3 , and arms l^2 , mounted 125 on the shaft L^3 on each side of the hopper. These arms are connected to the slide-valve L' by rods l^3 . The rods l and l^3 can be adjusted. As the shaft C^6 revolves the slide-valve L' is moved to close and open the mouth 130 of the hopper.

The operation of the machine is as follows: The hopper or receptacle L is charged with sand and the patterns are mounted upon the

heads of the plunger F. The operator places a flask X upon the stripper-plate E⁴, standing in front of the machine at W, Fig. 1. The machine is set in motion by an operator stepping upon the platform D², moving the flask under the sand-hopper L. In the meantime, while the machine is traversing the quarter-revolution the false flask G² is forced down upon the flask and after the flask is in position under the sand-hopper the valve is opened, allowing the sand to flow into the false flask and flask. Then the operator steps upon the platform again. Meantime another flask is placed in position and the first flask passes under the plunger, which compacts the sand around the pattern, forcing the sand out of the false flask G². As the flask travels from the plunger to the delivery position the frame G² is elevated and the flask passes under a strike-off N, which is secured to a bracket N', mounted on the post B'. This strike-off removes any sand that may project above the upper surface of the flask. The operator then steps upon the platform D² and removes the flask, the pattern in the meantime having been depressed so as to be entirely clear of the mold. Thus it will be seen that while the machine itself is automatic in its movements it cannot move from one point to another without the aid of an operator. In some instances the platform D² may be dispensed with, in which case the machine will be a continuously-operating machine.

I claim as my invention—

35 1. The combination in a molding-machine, of the sand-hopper, the plunger, the intermittently-movable carrying-frame, the pattern-carriers, a rail for elevating said pattern-carriers, a false flask, lever mechanism connected to the false flask, and a rail, said rail being so formed as to force the false flask down upon the flask, substantially as described.

2. The combination of the intermittently-operated carrying-frame, the vertically-movable pattern-carriers on said frame, a fixed cam-rail for vertically moving said pattern-carriers, a false flask also carried by the frame and adapted to be placed upon the flask, 50 a fixed rail for operating said false flask, star-gearing between the driven shaft and the carrying-frame and through the medium of which said frame is intermittently rotated, a

fixed sand-hopper, a valve therefor, a plunger, a cylinder beyond the sand-hopper, the plunger of said cylinder adapted to act upon the sand in the flask, a pump for forcing fluid under pressure into the cylinder and means geared to the driving mechanism of the machine for lifting the plunger, substantially as described.

3. The combination in a molding-machine, of a hydraulic cylinder, a plunger for compressing the sand in the flask, a driven shaft, a crank on said shaft adapted to lift the plunger, a pressure-regulating valve, and a cam on the shaft for positively opening said valve to release the plunger, substantially as set forth.

4. The combination in a molding-machine, of the standard, the carrying-frame, a sand-hopper, compression cylinder and plunger, a vertical shaft passing through the center of the standard, a horizontal shaft geared to said vertical shaft, a crank on said horizontal shaft, a gate-valve for the hopper connected to the crank, a regulating-valve for the cylinder, a cam on the horizontal shaft for operating said valve, a crank on the shaft engaging with the compression-plunger to lift it after being forced down by hydraulic pressure, substantially as described.

5. The combination of the central standard, the carrying-frame adapted to revolve around said standard, an annular trough in the base of the machine, scrapers mounted on the rotating carrying-frame and adapted to the annular trough, a receiving-box for the waste sand, said trough having an opening above said receiving-box, substantially as described.

6. The combination in a molding-machine, of the central standard, the mold-carrying frame, the sand-hopper and the compression-plunger, with hoods A⁴ and E⁵, a mercury seal between said hoods and a mercury seal between the standard and the upper portion of the mold-carrying frame, with a sand-trough into which the sand is directed from the hoods, substantially as described.

In testimony whereof I have signed my name to this specification in the presence of two subscribing witnesses.
